UNITED STATES PATENT OFFICE.

FAYE A. STEVENSON, OF LANCASTER, OHIO.

REFERENCE CALENDAR.

Application filed April 25, 1925. Serial No. 25,867.

To all whom it may concern:

Be it known that I, FAYE A. STEVENSON, a citizen of the United States, residing at Lancaster, in the county of Fairfield and State of Ohio, have invented a certain new and useful Reference Calendar, of which the following is a specification.

This invention relates to improvements in calendars and the present application is for the purpose of securing a patent on a certain modification and certain improvements which were not shown or described in my original and co-pending application No. 694,906, filed February 25, 1924 on an invention in perpetual calendars.

Although I consider the construction as shown and described in said co-pending application to be preferred in certain cases, yet the invention shown herein is considered novel and useful in many ways, and is considered an improvement on the invention shown in my said co-pending application in that it provides a means whereby all the year numerals are so arranged that they will all be exposed to view at the same time, thus making it easier to refer to the desired year almost immediately.

Other advantages of this invention will be noted in the following description and seen in the drawings in which like numerals represent like parts, and in which—

Figure 1 is a front face view of a calendar embodying my invention.

Figure 2 is a rear elevation of the same.

Figure 3 is a transverse section taken on line 3—3 of Figure 1.

Figure 4 is a front face view of the rear rotatable member detached.

Figure 5 is a similar view of the numeral-bearing or intermediate member detached.

In this invention, a face plate 1 is provided with a number slot 2, a month slot 3, and a hole 4 for suspending the device from a nail or pin. The face plate is preferably provided with a curved group of legends 5 about the number slot 2 to designate the names of the days of the week.

Arranged in the rear of the face plate 1 is a rotatable numeral-bearing member or disk 6. The rotatable member 6 is provided upon its front face with groups of numerals 7, and these groups are arranged in spiral over-lapping relation. The numerals in each group extend from 1 to 31 inclusive, in consecutive order, and the numeral 1 of one group is arranged above and adjacent to

the numeral 8 in the next group. The member 6 is provided with radial lines 8, as shown. The groups of numerals 7 are visible through the number slot 2, as clearly indicated in Figure 1. Disposed in the rear of the numeral-bearing member 6 is a rotatable month-bearing and year-bearing member or disk 9, having a larger diameter than the same. The month-bearing member 9 is provided upon its marginal edge projecting radially beyond the member 6 with month legends 10, and if desired and in certain instances, with legends 11, indicating the number of days in the particular month. When thus assembled, the month legends 10 are visible through the month opening 3. The members 6 and 9 are pivotally secured to the front plate 1 by means of a pivot element or pin 12. The month legends are arranged consecutively in chronological order.

Upon the rear face of the month-bearing member 9 are provided annular groups of numerals 13, which designate the years, between any given period, such as between 1925 and 1947. The leap years are underscored, and occur twice in close relation, as indicated at 14. A suitable legend 15 is preferably provided near the leap years. The month-bearing member 9 is provided with openings 16, corresponding in number and arrangement to the numerals 13 of the several years, and these openings are adapted to be brought into registration with an opening 17, formed upon the numeral-bearing member 6. A detachable fastening means 18 may be permanently held within the opening 17, and inserted within a selected opening 16, and locked therein.

To use, the numeral-bearing member 6 and the month-bearing member 9 may be turned with relation to each other, until the desired year is selected. If the calendar is to be used for the year 1925, then the member 6 is turned with relation to the member 9 until the pin 18 will enter the opening 16, adjacent the year 1925. This pin 18 will then hold the members 6 and 9 so that they may be rotated together. If the calendar for January 1925 is desired, the members 6 and 9 will be rotated until the January legend 10 is visible through the month slot 3. That portion of the numeral groups 7, visible through the numeral slot 2, in combination with the legends 5, constitute a calendar for January 1925. At the end of this month,

the members 6 and 9, locked together, are turned clockwise to bring the next month, February, to the slot 3, and the calendar for that month is accordingly provided. The 5 operation is continued in a similar manner throughout the entire year. When the calendar is adjusted for the month February, it is not turned for the next month, March, as the calendar is the same for these 10 two months. Besides providing a continuous calendar it is seen that the calendar for any month during any of the years shown may be referred to very quickly.

It will be noted that the groups of numerals 7 provide 31 days for each month, but I have printed the number of days for the months adjacent to the month designations. However, the number of days for a month may be determined, for the operator may 20 simply turn to the next month and by noting on which day of the week the first of the following month comes, he can quickly see on what day the previous month ends. It is seen that at the end of the year 1925, 25 a relative turning movement will be effected between the members 6 and 9 and the pin 18 carried by the member 6 will be inserted through the opening 16 adjacent the legend 1926.

30 It is noted that the leap year numerals are duplicated as seen in the series of numerals 13 on the back of the member 9. The two duplicated leap year designations have been underscored, or may be otherwise distinguished from the other year designations, as by printing in a different color, in order to notify the user of the device that the year is a leap year and since in all leap years February has 29 days it is necessary 35 for the user on the 29th day of February of a leap year, to again effect a relative turning movement between members 6 and 9, so that the pin 18 may be passed into the next opening 16 adjacent the next leap year 40 designation, so as to bring the members 6 and 9 in proper relation to each other to provide the calendar for the remaining months of that leap year.

Although the calendar shown in the 45 drawings is especially adapted for a certain number of years this period may be extended in various ways, as for example, by increasing the number of spaces for the year numerals 13. However, the year numerals may be ignored, in the operation of the calendar although they are preferably employed. By effecting a relative move-

ment between the members 6 and 9, for one space, at the end of each year, and an additional space on leap years, as above 60 described, it is seen that the device will display the correct calendar indefinitely. If desired, of course, the calendar may be printed or constructed to show the period between any other years instead of 1925 and 65 1947. For example, it can be constructed to show any date between 1915 and 1936. Also, by printing a second or a third row of numerals for additional years at one side of the annular group 13, the calendar 70 can be conveniently used to find any date during any period of 45 or 67 years depending upon the number of rows of year numerals which are added.

It is seen that calendars embodying my 75 invention may be made in a variety of different forms and used in different ways without departing from the essential principle discovered by me and shown and described in the present application and so disclosed in my co-pending application above referred to. It is apparent that there are many ways of applying this principle of mine, other than in the particular forms I have shown. 85

I claim:

A calendar comprising a face-plate having a number slot and month display means, a rotatable member positioned in the rear of said face-plate and provided with numerals indicating the days of the month, such numerals being visible through the number slot, a second rotatable member in the rear of the face-plate and having month designations arranged consecutively thereon and adapted to be indicated by said month display means, the second rotatable member being provided upon its rear face with a group of year designations arranged thereon in numerical order and having openings corresponding in number and arrangement to said year designations, and a locking element carried by the first named rotatable member and adapted to be inserted within a selected opening of the second named 100 rotatable member so that the said members may be locked together to rotate as a unit. 105

In testimony whereof I affix my signature in presence of two witnesses.

FAYE A. STEVENSON.
